CLAIM

The ornamental design for a connector for connecting objects to a rod as shown and described.

DESCRIPTION

FIG. 1 is a perspective view of a connector for connecting objects to a rod showing my new design; FIG. 2 is a front elevational view thereof; FIG. 3 is a rear elevational view thereof; FIG. 4 is a left elevational view thereof; FIG. 5 is a right elevational view thereof; FIG. 6 is a top view thereof; FIG. 7 is a bottom view thereof; FIG. 8 is a perspective view of the connector for connecting objects to a rod viewed from another direction; FIG. 9 is a perspective view of the connector for connecting objects to a rod showing a first use aspect; FIG. 10 is a perspective view of the connector for connecting objects to a rod showing a second use aspect; and, FIG. 11 is a perspective view of the connector for connecting objects to a rod showing a third use aspect.

The broken lines in the drawings depict portions of the connector for connecting objects to a rod that form no part of the claimed design.

The additional broken lines in FIGS. 9-11 depict environmental subject matter that forms no part of the claimed design.
